UNITED STATES PATENT OFFICE

JOHN N. COLLINS, OF ROSEDALE, NEW YORK

COLLAR

Application filed April 2, 1929. Serial No. 351,900.

REISSUED

My invention relates to a collar, and particularly to a collar with stiffening means at the front edges.

It is the principal object of the invention 5 to provide a collar having improved stiffening means along the front edges, arranged and embodied so as to be readily and cheaply manufactured, neat in appearance and serviceable in use.

10 Other minor objects and features of the invention will appear as the specification proceeds.

In the drawings, which show for illustrative purposes only, preferred forms of the invention—

Fig. 1 is a front view of a collar, one corner being turned up to illustrate features at the rear of such corner;

Fig. 2 is a somewhat diagrammatic view of 20 parts of a collar before being stitched;

Fig. 3 is a view of the parts shown in Fig. 2 and partially stitched together;

Fig. 4 is a sectional view taken substantially in the plane of the line 4—4 of Fig. 3;

25 Fig. 5 is a view similar to Fig. 4 but illustrating a slight modification.

The construction and features of invention may perhaps best be described in connection with a description of the preferred method 30 of manufacture.

In the drawings, 6 indicates an inner ply, while 7 indicates an outer ply of a collar. These plies as is usual in collar manufacture are arranged with the wrong side of the goods 35 outwardly. If desired, a ply of interlining 8 may be interposed between the plies 6—7. Another ply which for convenience I term a pocket ply 9 is interposed between the plies 6—7. In the form shown the pocket ply is 40 formed of one thickness of goods folded upon itself (with the right side of the goods outwardly) and with the edges lying substantially along the edges of the front of the plies 6—7. The top edges of the pocket ply may 45 be folded inwardly as indicated by the dotted line 11 so as to leave a finished edge 10 at the top.

All of the plies shown in Fig. 2 may then 50 be stitched together by a common seam along the front edge as indicated more particularly

at 12. The plies are also stitched along the bottom edge. The stitched together collar construction is then folded back so that the seam 12 will come at the extreme front edge of the collar and the fold of the ply 9 will 55 extend outwardly as partially indicated at 13 in Fig. 3. The ply 9 is then folded back along the rear side of the rear ply 6 and is then stitched to the remaining plies as indicated at 14 so as to leave a pocket 15 extending well 60 up toward the top of the collar as indicated more particularly at 16 in Fig. 1. The open pocket 15 may then receive a stiffening member such as a celluloid strip 17 so that the front 65 corners of the collar will be held straight and will not curl up. The pocket ply is preferably made of the same goods as that of the collar especially when colored or figured fabrics are employed. By means of my improved construction no additional seams are required 70 and the labor and material costs in the manufacture of my collar are only trivially increased over the cost of corresponding collars 75 without my improved pocket construction.

In that form of the invention shown in Fig. 5 substantially the same construction is employed and the method of manufacture is substantially the same as that heretofore described, except that instead of employing a 80 separate stiffener 17 which may be removed I 80 employ one or more plies such as stiff interlining material as indicated at 18 and preferably enclosed within a double thickness 85 ply 9', which by analogy may be termed a pocket ply. The construction shown in Fig. 5 with a proper grade of stiff material will be substantially non-curling and a collar so made will be found to be satisfactory in use.

While the invention has been described in 90 considerable detail and a preferred form illustrated I do not wish to be strictly limited to the various details specifically disclosed, since obviously some changes may be made within the scope of the invention as defined 95 in the appended claims.

I claim:

1. A collar including an outer ply, an inner ply, and an interlining ply together with a pocket ply interposed between said inner and outer plies and adjacent said inter-

lining ply, all of said plies being stitched together by a common seam at the extreme edge of the collar, said pocket ply extending around the extreme outer edge of said inner 5 ply and extending rearwardly thereof, and all of said plies being stitched together by a common seam substantially parallel to said first mentioned seam and lying at the rear edge of said pocket ply.

10. 2. A collar including outer and inner plies, a pocket ply, one edge of said pocket ply being interposed and held between the inner and outer plies, a seam at the extreme edge of said collar securing said plies together, 15 the exposed part of the pocket ply being turned back along the rear of the inner ply, and a row of stitches penetrating all of said plies to hold the pocket ply in position at the rear of said inner ply.

20. 3. A collar including outer and inner plies, a pocket ply, one edge of said pocket being interposed between the inner and outer ply adjacent their edges, the exposed part of the pocket ply being turned back along the underside of the inner ply, and a row of stitches penetrating all of said plies in folded position to hold the pocket ply closely adjacent the underside of said inner ply.

25. 4. A collar including outer and inner plies and a pocket ply, one edge of said pocket ply being interposed between said inner and outer plies adjacent their edges, all of said plies being stitched together by a common seam at the extreme edge of the collar, the exposed 30 part of said pocket ply being turned back along the underside of said inner ply, said pocket ply and said inner ply being stitched together by a seam substantially parallel to said first mentioned seam so as to hold said 35 pocket ply closely adjacent the under side of said inner ply.

JOHN N. COLLINS.
